UNITED STATES PATENT OFFICE.

ROYDEN K. McDUGAL, OF LINCOLN, NEBRASKA.

SPARK-PLUG ATTACHMENT.

1,137,992.

Specification of Letters Patent.

Patented May 4, 1915.

Application filed March 11, 1912. Serial No. 682,958.

To all whom it may concern:

Be it known that I, ROYDEN K. McDUGAL, a citizen of the United States, residing at Lincoln, in the county of Lancaster and State of Nebraska, have invented certain new and useful Improvements in Spark-Plug Attachments, of which the following is a specification.

The present invention relates to a device 10 to be applied to a spark plug for short circuiting parts thereof, to cut the sparking points out of circuit, whereby the spark plug will be deadened.

An important object of this invention is 15 to provide a device of the above mentioned character, which may be quickly and easily placed upon the spark plug, will remain in place thereon until removed, and may be placed upon spark plugs of different sizes.

20 A further object of this invention is to provide a device of the above mentioned character, which is simple in construction, compact in arrangement of parts, and cheap to manufacture.

25 Other objects and advantages of the invention will be apparent during the course of the following description.

In the accompanying drawings forming a 30 part of this specification and in which like numerals are employed to designate like parts throughout the same, Figure 1 is a side view of the device applied to a spark plug, Fig. 2 is a plan view of the same, and, Fig. 3 is a front elevation of the device removed 35 from the spark plug.

In the drawings wherein for the sake of illustration, I have shown a preferred embodiment of my invention, the numeral 1 designates the outer sleeve or body portion 40 of the spark plug, which is externally screw-threaded, as shown, for insertion within a screw-threaded opening 2 formed through the head of a cylinder 3 of an explosive engine. The outer sleeve 1 is provided at its 45 upper end with an enlarged head 4, as shown. Extending longitudinally within the sleeve 1 is an insulating plug 5, properly held therein by a clamping ring or gland 6. Extending axially within the insulating plug 5 50 is a rod terminating at its lower end in a sparking point 7, which is insulated from the sleeve 1. This sparking point has electrical connection at its upper end with a metallic head 8 to which is connected a feed 55 wire (not shown) by means of a contact or

clamping nut 9. Electrically connected with the metallic outer sleeve 1 is a co-acting sparking point 10, having its free end disposed a suitable distance from the sparking point 7 to form an air gap therebetween. 60 The spark plug is shown and described simply to more clearly illustrate the application of the present invention, for which reason it is thought that no further detailed description of the same need be given. It is to be understood that the invention is not in any sense restricted in use to the particular form of spark plug shown and described as it may be just as advantageously applied to other spark plugs. 70

My spark plug attachment comprises a handle 11, which is formed of any suitable insulating material, such as porcelain, wood, hard rubber or fiber. Rigidly connected with one end of the handle 11 is a body portion 12, disposed at a right angle thereto, as shown. The body portion 12 has its lower end portion 13 off-set outwardly, as shown. It is thus seen that the upper end of the body portion 12 is positioned forwardly of the lower end thereof. The body portion 12 may be formed of any suitable metal which is a good conductor of electricity. 75

Rigidly connected with the upper and lower ends of the body portion 1 are metal 80 small and large substantially U-shaped spring clips or brackets 14 and 15, respectively. The small clip or bracket 14 is adapted to engage with the metallic head 8, while the large clip or bracket 15 engages the head 4. The large clip or bracket 15 is longer than the upper small bracket 14 but by virtue of the fact that the lower portion 13 of the body portion 12 is off-set outwardly, as above stated, the ends of the clip or bracket 15 terminate in substantially the same plane with ends of the clip or bracket 14. The spring clips or brackets 14 and 15 have their free ends bent or curved outwardly, as shown at 16. These spring clips or brackets have their sides bent inwardly near the body portion 12, as shown at 17. 95

The operation of the device is as follows:—When it is desired to short circuit portions of the spark plug to deaden the same or cut the sparking points 7 and 10 out of circuit, the operator takes hold of the handle 11 and places the free or curved ends 16 of the spring clips or brackets 14 and 15 in engagement, respectively, with the heads 110

- 2
- 8 and 4. He then pushes on the handle 10 to place these spring clips upon their respective heads. It is thus seen that the circuit will now be completed through the head 8, 5 upper clip 14, body portion 12, lower clip 15, head 4 and back to the ground. The device will remain in place until removed by the operator, which enables him to examine the other cylinder or parts of the engine. 10 In this way he is able to find out which cylinder is not operating. Assuming that there are two cylinders provided with spark plugs and one of these spark plugs is not operating, it is obvious that as soon as my device 15 is applied to the spark plug which is operating, such spark plug will be deadened and the engine stopped. In this way it is ascertained that the other spark plug is not operating.
- 20 It is to be understood that the form of my invention herewith shown and described is to be taken as a preferred example of the same and that certain changes in the shape, size, and arrangement of parts may be 25 sorted to without departing from the spirit of the invention or the scope of the subjoined claim.

Having thus described my invention, I claim:

In a device for electrically connecting the two metallic elements of a spark plug, comprising a relatively rigid metallic body portion having its lower end laterally and outwardly offset; an approximately U-shaped resilient metallic clamp attached to the upper end of the relatively rigid body portion; a second approximately U-shaped resilient metallic clamp attached to the lower outwardly offset end of the relatively rigid body portion and being substantially longer than the first named clamp whereby its free end is substantially co-extensive in length with the corresponding end of the first named clamp; and an insulating handle secured to the relatively rigid body portion between the clamps, whereby the clamps may be readily detachably mounted upon and removed from the elements of the spark plug.

In testimony whereof I affix my signature in presence of two witnesses.

R. K. McDUGAL.
